Primary Examiner — Mary Ann Calabrese(74) *Attorney, Agent, or Firm* — Tucker Ellis LLP(57) **CLAIM**

The ornamental design for a table, as shown and described.

DESCRIPTION

FIG. 1 is a front-right-top perspective view of a table showing my new design;

FIG. 2 is a front-left-bottom perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is a front-right-top perspective view of the table with the slide-outs shown in an alternate extended position of use;

FIG. 10 is a front-left-bottom perspective view thereof;

FIG. 11 is a top view thereof;

FIG. 12 is a bottom view thereof;

FIG. 13 is a front view thereof;

FIG. 14 is a rear view thereof;

FIG. 15 is a left side view thereof; and,

FIG. 16 is a right side view thereof.

The broken lines and areas within shown in white overlay show portions of the table that form no part of the claimed design.

1 Claim, 13 Drawing Sheets(56)
